UNITED STATES PATENT OFFICE.

JOSEPH B. CLAY, OF CEDAR FALLS, IOWA.

FARROW RAIL.

Application filed July 15, 1921. Serial No. 484,972.

My invention belongs to that general class of devices known as farrow rails, and relates particularly to a farrow rail for use in hog pens or the like. The invention has 5 among its objects the production of a device of the kind described that is simple, inexpensive, durable, reliable, sanitary, attractive, efficient and satisfactory for use wherever found applicable. It has particularly as 10 an object the production of a device of the kind described which may be adjusted as desired, and which may be swung out of the way when it is not desired to use the same. Many other objects and advantages 15 of the construction herein shown and described will be obvious to those skilled in the art from the disclosure herein given.

To this end my invention consists in the novel construction, arrangement and combination of parts herein shown and described, 20 and more particularly pointed out in the claims.

In the drawings, wherein like reference characters indicate like or corresponding 25 parts,

Fig. 1 is a view in elevation of a portion of a hog pen enclosure with my device applied thereto;

Fig. 2 is a sectional view taken substantially on the line 2—2 of Fig. 1;

Fig. 3 is an enlarged sectional view taken substantially on line 3—3 of Fig. 1;

Fig. 4 is a sectional view taken substantially on line 4—4 of Fig. 1;

Fig. 5 is a sectional view taken substantially on line 5—5 of Fig. 1;

Fig. 6 is a sectional view taken substantially on line 6—6 of Fig. 1;

Fig. 7 is a view in elevation of a wall bracket;

Fig. 8 is a sectional view taken substantially on line 8—8 of Fig. 1, showing the parts enlarged;

Fig. 9 is an elevational view of the parts shown in Fig. 8;

Fig. 10 is a sectional view taken substantially on line 10—10 of Fig. 11;

Fig. 11 is a plan view of the parts shown in Fig. 10 as seen from above;

Fig. 12 is a sectional view taken substantially on line 12—12 of Fig. 10, and

Fig. 13 is a sectional view taken substantially on line 13—13 of Fig. 10.

Referring to the drawings, in which only one of the pen walls is shown, 1 represents a frame of suitable size, shape and material which may carry the wire fabric or netting 2, the same constituting one of the enclosing walls of the pen. The several panels are supported, in the construction shown, by posts 3, or the equivalent, the panels being secured to the posts by fittings or brackets 4 and 5, or equivalent means for the purpose. In the construction shown, the panel is braced intermediate its ends by angle bars 6, which are secured to the frame 1 by fittings 7, or their equivalents, said angle bars being spaced apart as shown in Fig. 8.

Carried by the walls of the enclosure, as for example by the panel end frame 1, is a farrow rail 9, it being understood that the rails may be arranged at one or both sides of the panel, his depending upon whether or not the panel divides the different pens. Where there is no pen on one side, the rail may be omitted at that side. As shown, each rail is bent or offset adjacent the ends so that when in the position shown in Fig. 2 the same is spaced throughout the greater part of its length from the wall or partition. As shown, the same is pivotally secured to the panel or the equivalent, as for example, it may be secured to the uprights of the frame in any suitable manner. In the construction shown I provide cooperating bracket members 10 and 11 which are secured on the frame 1 by bolts 12 or their equivalents. One of the bracket parts, bracket 10, is extended, as at 13, so as to provide sockets or recesses into which the ends of the rails 9—9 are inserted and pivotally secured and supported.

In Fig. 1, I have illustrated the farrow rail in operative position in the full lines, and in dotted lines raised out of operative position. The same may be supported and maintained in operative position in any suitable manner, the supporting means shown comprising the extending arm members 14 which are carried between the upper and lower plates or brackets 15 and 16 respectively.

tively, said plates being arranged on the angle braces 6. Referring to Fig. 3, the plates or brackets 15 are secured to the angle braces 6 by bolts 17, the angle irons 5 being provided with the desired number of holes so that the brackets may be supported at the desired height depending upon the desired distance of the brackets 10-11 from the floor and the desired position of 10 the farrow rail. As shown, parts 14 are provided with journal posts 18, so that they may be pivotally carried by the brackets 15 and 16. The outer ends of the parts 14 are provided with means for clamping the 15 farrow rail and holding it in operative position so as to be spaced from the panel, said clamping means comprising a jaw 20, preferably integral with said parts at their outermost ends, and a cooperating jaw member 21 pivoted at 22 to the jaw member 20 and adapted to encircle the farrow rail 9, as shown in Figs. 3 and 10. The jaw member 21 extends rearwardly of the pivotal axis 22 and forms a lever arm 23, said lever arm being preferably tapered across its width so that a lock member 24, slidable on the horizontal web 25 of the part 14, may be moved or slid to both said members to release or clamp said pivoted jaw member 21 30 about the farrow rail 9, depending upon which way said locking means 24 is moved. The upper brackets 15 are not fixedly secured to the angle arms, but have a rearwardly extending web 8 terminating in an outer enlarged head 8', said web being adapted to snugly and slidably fit in the space between the opposed, parallel angle irons 6, thus preventing any side play or lateral movement of the bracket 15. The 40 upper bracket 15 is provided with upturned or hook ends 26, the tips of said upturned ends being at greater radial distance from the pivotal axis of the farrow rail than the central or midportion of said rail so that 45 after the rail has been released from the holding jaws, it may be swung upwardly over the ends 26 and held in place against the angle irons 6. The parts 14 are provided with projections or auxiliary arms 50 27 near their upper ends, said auxiliary arms being adapted to abut the rail 9 when said rail is held in its inoperative position in the brackets 15. When it is desired 55 to place or position the farrow rails in inoperative position, as indicated in Figs. 1, 8 and 9, the jaws 20 and 21 are released by sliding the locking member 24 and the part 14 is swung against the panel, permitting 60 the yieldable rail 9 to be swung upwardly and sprung over the end 15, against the bars 6. The part 14 cannot be swung outwardly 65 from the panel section, as this is prevented by the projection 27 abutting against the inoperative rail 9, hence there is no danger of the jaws or other portions of the arms ever

being extended when the rail is inoperative and causing damage or injury to the occupants of the pen.

While I have particularly illustrated the device in Figs. 1 to 6 as applied to a steel or 70 similar enclosure or fence, the same, where desired, may be applied to the wall of a building or other support by means of brackets like that shown in Fig. 7. In this case 28 represents the bracket correspond- 75 ing to a half of the brackets or fittings 10-11. The same is similar to the brackets previously described, except that it is provided with a flat flange whereby it may be secured in place by bolts or screws 29, or 80 equivalent means for the purpose. In this case the plate or brackets 15 and 16 may be secured directly to the wall intermediate the brackets 28. Obviously, this construction operates in a similar manner to the 85 other construction described.

The rail herein shown is not only exceedingly simple, convenient and efficient, but it is also sanitary and attractive. It may be adjusted as necessary, depending upon the 90 size of the hog, etc., and may be made of the desired sizes to fit the various sized pens. It will be particularly noted that as the same is constructed, none of the farrow rails interfere and they may be operated 95 singly or all together as desired. Where the rail is not necessary, the same may be raised to an inoperative position, giving that much additional room in the pen, as well as facilitating cleaning. The fasten- 100 ings are so simple that the rails may be easily adjusted or removed at will. When the pen, however, contains a litter of pigs, the rails about the inside of the pen may be placed in operative position, thereby pre- 105 venting the small pigs from being crushed, rolled on and smothered, or otherwise injured.

Having thus described my invention, it is obvious that various other immaterial 110 modifications may be made in the same without departing from the spirit of my invention; hence I do not wish to be understood as limiting myself to the exact form, construction, arrangement and combination 115 of parts herein shown and described, or uses mentioned.

What I claim as new and desire to secure by Letters Patent is:

1. In a device of the kind described and 120 in combination, a rail having parts offset laterally at its ends, means for pivotally supporting said rail at said ends, and means movable independently of said rail about an axis transversely of the pivotal axis of said rail for detachably engaging said rail intermediate its ends and supporting it in operative position.

2. In a device of the kind described and 130 in combination, a wall unit including a

frame and means for securing the same in place, a farrow rail and means for pivotally supporting the same at each end of the frame, said rail being offset adjacent each 5 end outwardly from the section, and adjustable means carried pivotally by the section and separate from said pivotally supporting means and extending laterally therefrom for detachably engaging said rail intermediate 10 its ends and supporting the same in operative position.

3. In a device of the kind described and in combination, a fence unit including a frame, brackets arranged at each end of said 15 frame and provided with recesses therein at each side of the frame, farrow rails arranged at each side of said frame with their ends positioned in the recesses in said brackets, said rails being offset adjacent the ends 20 whereby the same are spaced from the fence unit between the ends, a brace bar connecting the top and bottom sides of the frame of the fence unit, and arms arranged on each side of the unit carried by said brace bar 25 for supporting said rails in operative relation with the frame, said arms being movable against the frame whereby the rails may be moved out of operative position.

4. In a device of the kind described and 30 in combination, a fence unit including a frame, brackets arranged at each end of said frame and each provided with recesses therein at each side of the frame, farrow rails arranged at each side of said frame 35 with their ends disposed in the recesses in said brackets, said rails offset adjacent the ends whereby the same are spaced from the fence unit between the ends, a bar extending between the top and bottom sides of the 40 frame of the fence unit, and arms arranged on each side of the section and pivotally carried by said bar for maintaining said rails in operative relation with the frame, said arms independently movable against 45 the frame, whereby either one of the rails may be moved out of operative position.

5. In a device of the kind described and 50 in combination, a farrow rail, means at each end for pivotally supporting said rail, and means for maintaining the rail in operative position spaced from the enclosure wall, comprising an arm mounted upon said supporting means and hinged on an axis transverse of the pivotal axis of said rail 55 so as to be swung out of the way of the rail when the rail is dropped and provided with means for detachably engaging and holding said rail.

6. In a device of the kind described and 60 in combination, a farrow rail, means at each end for pivotally supporting the rail, and means for maintaining the rail in operative position spaced from the enclosure wall, comprising a hinged arm mounted between 65 said supporting means, and provided with

pivoted clamped jaws for detachably holding the rail.

7. In a device of the kind described and in combination, a farrow rail, means at each 70 end for pivotally supporting the rail, and means for maintaining the rail in operative position spaced from the enclosure wall, comprising a hinged arm mounted between said supporting means, and provided with a jaw for detachably supporting the rail, 75 a second jaw member pivoted to said arm and cooperating with said first mentioned jaw to clamp said rail therebetween, and means for holding said jaws in operative position.

8. In a device of the kind described and in combination, a farrow rail, means at each 80 end for pivotally supporting the rail, and means for maintaining the rail in operative position spaced from the enclosure wall, comprising a hinged arm mounted between said supporting means, and provided with a jaw for detachably supporting the rail, 85 a second jaw member pivoted to said arm and cooperating with said first mentioned jaw to clamp said rail therebetween, and having a tapered lever arm extending rearwardly from the rail engaging end, and means slidably engageable with said lever arm to move said jaws relatively of each 90 other for clamping and releasing said rail therebetween.

9. In a device of the kind described and in combination, a fence unit including a 95 frame, brackets arranged at the ends of said frame, a farrow rail pivotally supported at its ends in said brackets, said rail being offset laterally at its ends, means adapted to be moved into operative position for engaging said rail and supporting it in operative position and to be moved to inoperative position to permit said rail to drop, and means for supporting said rail after it has been swung upwardly to its inoperative position and maintaining it in said position.

10. In a device of the kind described and in combination, a fence unit including a frame, brackets arranged at the ends of said frame, a farrow rail pivotally supported at its ends in said brackets, said rail being offset laterally at its ends, a brace bar connecting the top and bottom of said frame, means for engaging and supporting said rail in operative position, and hook means carried by said brace bar for engaging and supporting said rail after it has been swung upwardly to its inoperative position, the outer end of said hook being at a greater distance from the pivotal axis of the farrow rail than the hook-engaged portion of the rail, whereby the rail must be sprung in place over said hook.

11. In a device of the kind described and in combination, a fence unit including 115 a frame, brackets arranged at the ends of

said frame, a farrow rail pivotally supported at its ends in said brackets, said rail being offset laterally at its ends, a pivotally mounted arm for engaging and supporting said rail in operative position, said arm being movable against the frame, and means for supporting said rail after it has been swung upwardly to its operative position,

said arm having means thereon engageable with said rail in its inoperative position to prevent the accidental pivotal movement of the arm and holding it against the frame.

In testimony whereof, I have hereunto signed my name.

JOSEPH B. CLAY.
